UNITED STATES PATENT OFFICE.

CHARLES EDWARD HAVILAND, OF LIMOGES, FRANCE.

DESIGN FOR A PITCHER.

SPECIFICATION forming part of Design No. 28,970, dated July 5, 1898.

Application filed June 1, 1898. Serial No. 682,304. Term of patent 7 years.

To all whom it may concern:

Be it known that I, CHARLES EDWARD HAVILAND, a citizen of the United States, residing at the city of Limoges, in the Republic of France, have invented and produced a new and original Design for a Pitcher or Receptacle, of which the following is a specification, reference being had to the accompanying drawings, forming part thereof, and in

10 which—

Figure 1 is a side elevation of a pitcher bearing and incorporating my design, and Fig. 2 is a horizontal section of same on the dotted line 2 2 of Fig. 1.

15 The leading features of my design consist of the shape of the body of the pitcher or receptacle and the ornamental configuration thereon, as shown.

20 The body of the pitcher or receptacle comprises the upper and lower sections lettered, respectively, B C, the upper section B having the sides, which swell outward to meet the

upper edges of the lower section C, whose sides curve inward and downward to the base D, as shown.

25 The upper portion of the section B has an ornamental edging E, and the upper portion of the section C has a like ornamental edging F, directly above which the lower edge of the upper section B bears the ornamental band G. 30 The lower section C bears the scalloped scroll ornamentation H, extending on scalloped lines around the lower portion of the pitcher.

The pouring-spout is lettered I, and the handle is designated by the letter A. 35

What I claim is—

The design for a pitcher or receptacle, substantially as shown and described.

Signed at New York, in the county and State of New York, this 31st day of May, A. D. 1898. 40

CHARLES EDWARD HAVILAND.

Witnesses:

EDWIN HAVILAND,
CHAS. C. GILL.
